BINDING

Charles Edward Emmer and Livio Anthony Valli,
Chicago, Ill., assignors to General Binding Cor-
poration, Chicago, Ill., a corporation of Illinois

Application June 2, 1945, Serial No. 597,198

2 Claims. (Cl. 129—9)

1

This invention relates to a binding for loose-leaf binders and the like, and more particularly to a binding having binding rings formed by opposed ring portions mounted on relatively movable members.

It is an object of this invention to provide a looseleaf binding in which cooperable ring portions are carried by relatively slid able members for opening and closing of the rings by movement of said members.

Another object is the provision of a loose-leaf binding having separable ring portions which are disposed in offset relation upon separation thereof to open the rings.

It is a further object of the invention to provide a loose-leaf binding in which relatively slid able members carry cooperable ring portions which abut to provide closed rings in one position of the members and are separated to open the rings in another position of said members.

It is also an object to provide a loose-leaf binding in which relatively slid able members carry cooperable ring portions providing a plurality of closed rings in one position of said members, and being separated for opening the rings in another position of said members, which have means for locking them in their ring-closing position.

An additional object of the invention is the provision of a loose-leaf binding in which resilient ring portions are carried by a pair of relatively slid able members and adapted for resilient abutting engagement upon movement of said members in one direction so as to provide tightly closed rings.

A still further object is the provision of a loose-leaf binding in which cooperable ring portions are carried by relatively slid able members for opening and closing of the rings, the slid able members having means to guide and limit the movement thereof.

Other and further objects and advantages of the present invention will be apparent to those skilled in the art from the following description and the appended drawings.

On the drawing:

Figure 1 is a fragmentary plan view of a loose-leaf binder having applied thereto the binding of this invention;

Figure 2 is an enlarged fragmentary sectional view taken along the line II—II of Figure 1;

Figure 3 is a fragmentary plan view of the binding of this invention in closed position, with parts in section;

Figure 4 is a view similar to Figure 3, but showing the parts in open position;

Figure 5 is a view similar to Figure 4, but showing a slightly modified form of the invention; and

Figure 6 is a view similar to Figure 3, but

2

illustrating a still further modified form of the invention.

The binding is shown in Figures 1 and 2 as applied to a loose-leaf binder 10 having a back 11, with sheets 12 therein. Apertures 13 are provided along a margin of the sheets 12 for securing of the sheets in the binder.

The binding comprises a pair of plates 14 and 15, the plate 15 overlying the plate 14. Extending upwardly from one edge of the plate 14 are spaced prongs or ring portions 16. From the edge of the plate 15 remote from the ring portions 16 there extend upwardly spaced ring portions 17. The ends of the ring portions 16 and 17 are adapted to meet in closed position of the binding to provide a plurality of closed rings. The ring portions 16 and 17 may be resilient, and if desired may have a combined extent transversely of the plates greater than the combined width of the plates in locked position, for the purpose explained below. Means may be provided on the plate 15 to facilitate clasping thereof for moving the plates relative to each other, such as the vertically extending lug or tab 18. The binding may be secured to the binder 10 in any suitable manner, as by riveting to the back 11.

As best shown in Figures 3 and 4, the plate 15 is provided with slots 19 which extend at an angle to the axis of the plate, and have oppositely disposed end portion 19a and 19b which extend parallel to the axis. The plate 14 is provided with projections 20 each extending into one of the slots 19 and preferably provided with a head or lateral projection wider than the slot 35 so as to prevent separation of the plates. As shown in Figure 2, the projections may take the form of rivets. Instead of rivets, headed pins or other projections integral with the plate 14 may, of course, be employed. The end portions 19a 40 of the slots are those adjacent the edge of the plate 15 nearer the ring portions 16, and the end portions 19b are more remote from that edge of the plate.

With the elements of the binding in the position shown in Figures 1 and 3, the portions 16 and 17 provide closed rings. By drawing the plate 15 downwardly as viewed in Figure 3, the plate 15 will be moved downwardly and to the right relative to the plate 14, as shown in Figure 4, by reason of the coaction of the slots 19 and the projections 20. The plates 14 and 15 are thus shifted both transversely and longitudinally, so that the ring portions 16 and 17 are separated transversely and at the same time offset from each other longitudinally of the plates. The end portions 19a and 19b of the slots 19 cause the initial and final movements of the plates to be in the longitudinal or axial direction, so that the ring portions in being separated are first moved apart longitudinally of

the plates, and similarly, are moved longitudinally of the plates into registry and alignment with each other in closing of the binding.

The ring portions 16 and 17 may be made resilient and utilized to make a tight joint, or in other words a tightly closed ring, by so forming the ring portions that the free ends thereof come into abutting contact before the plates 14 and 15 come into fully closed position in the closing of the binding. Thus, the rings are slightly greater in extent than the width of the plates and when the plate 15 is positioned over the plate 14 the resilient ring portions 17 are urged tightly together at the free ends thereof to prevent any gapping in the ring.

When the plates are in closed position, they are held locked by the engagement of the projections 20 in the end portions 19b of the slots 19 and the engagement of the edge of the plate 15 against the feet of the ring portions 16. The projections 20 on the plate 14 are so spaced from the feet of the ring portions 16, and the end portions 19b of the slots 19 are so located in the plate 15, that the plate 15 is jammed or wedged against the ring portions 16 when the projections 20 are in the slot portions 19b, and the binding elements are thus held against accidental unlocking or opening. The end portions 19a may be omitted if desired but preferably are provided to hold the plates against relative transverse movement in open position of the binding by engagement of the projections 20 therein.

In Figure 5, a modified construction of the binding is illustrated in which the slot 19 has an end portion 19c, corresponding in position to the end portion 19b above described, extending at a slight angle to the axis of the plate 15 instead of parallel thereto, so that as the plates 14 and 15 are moved to closed position they have a relative wedging movement into the final locked position. The slot 19 and end portion 19c are so proportioned and located on the plate 15 in relation to the lip 16 and rivet 20 that this final wedging movement occurs after the edge of the plate 15 has reached a position close to or axially in contact with the lip 16.

In Figure 6, there is illustrated a construction of the binding by which the rings may be opened by relative movement of the plates 14 and 15 in either longitudinal direction, and closed by movement of the plates in the reverse direction. Instead of the diagonal slot 19 provided in the other forms of the invention, a generally V-shaped slot 21 is provided in the plate 15, having two branches 22. Each branch 22 of the slot extends from a notch 23 at the junction of the branches diagonally toward the edge of the plate 15 adjacent the ring portions 16 of the plate 14. Oppositely extending end portions 22a are provided at the ends of the branches 22 adjacent this edge of the plate. These slot end portions correspond to the end portions 19a previously described. The projection 20 on the plate 14 is engaged in this slot 21, and the projection and slot are so located that when the plates 14 and 15 are in locked position the projection 20 engages in the notch 23. A tongue 23a is formed in the plate 15 opposite the notch 23 to provide a sufficiently constricted space for snug reception of the projection 20 in the notch. The pressure of the tongue 23a against the projection holds the parts against unintentional movement.

The plate 15 thus may be urged longitudinally in either direction to be moved both longitudinally and transversely by reason of the coaction

of the rivet 20 with one or the other of the branches 22 of the slot. The ring portions 16 and 17 are thus separated transversely and moved to offset position relative to each other longitudinally of the plates. Relative movement of the plates in the opposite direction then results in the ring portions being brought into engagement and alignment to provide rings for holding the sheets 12 in the binder 10. The notch 23 serves as a locking portion of the slot 21, so that relative movement of the rivet 20 out of the notch 23 and into one of the slot branches 22 must occur before any substantial opening of the rings may take place. The tongue 23a and notch 23 also provide means for causing final wedging action of the plates when moved to locked position, being positioned slightly farther from the edge of the plate 15 adjacent the ring portions 16 than the other portions of the slot 21. The notch 23 in this respect is similar to the end portion 19c of the slot 19 of the binding illustrated in Figure 5.

If desired, the plate 14 may be so formed as not to contact the ring portions 16, and the portions 16 and 17 formed to have a combined extent transversely of the plates greater than the distance across the plates in their locked position. The plates are locked by reason of the resilient pressure of the ring portions 16 and 17 against each other.

On the other hand, the ring portions 16 and 17 may be made of a size such that the rings provided thereby are of the same extent as the width of the plates, so that the ring portions are in snug abutting relation in closed position of the binding, without exerting any pressure on each other. The ring portions may therefore be either resilient or rigid, as may be convenient or desirable. With such a construction, of course, the ring portions 16 and 17 are not relied upon to lock the plates in closed position.

As shown, the free ends of the ring portions 16 and 17 of the bindings illustrated in Figures 1 to 5, inclusive, are preferably formed at an angle. If for any reason a slight separation of the ring portions takes place, the sheets 12 will still be held by the rings, since the extreme ends of the ring portions will be in lapped relation transversely, though spaced longitudinally, of the plates. The angled ends of the ring portions 16 and 17 also facilitate the engagement and disengagement of the ring portions in the closing and opening of the rings, and particularly in the case of the ring portions resiliently pressing each other as described above.

In the construction illustrated in Figure 6, however, the ends of the ring portions 16 and 17 are formed to parallel the axis of the plates, so there will be no interference with movements of the ring portions and plates in either longitudinal direction.

The offsetting of the ring portions 16 and 17 longitudinally of the plates in open position of the binder prevents the sheets 12 from becoming caught on the ring portions of one plate when it is desired to engage the sheets on the ring portions of the other plate, since the apertures 13 of the sheet can be aligned with only one set of ring portions and the other set therefore cannot catch in the apertures. At the same time, sheets may readily be inserted or removed by reason of the separation of the ring portions 16 and 17 transversely of the plates.

It will, of course, be understood that various details of construction may be varied through a

wide range without departing from the principles of this invention and it is, therefore, not the purpose to limit the patent granted hereon otherwise than necessitated by the scope of the appended claims.

We claim as our invention:

1. A loose-leaf binding comprising a pair of plates relatively slidable on each other, a plurality of ring portions on each plate engageable to provide a plurality of closed rings, the ring portions on each plate being aligned in parallelism with those of the other plate, a generally V-shaped slot in one plate having its apex remote from the ring portions of the other plate, a projection on the other plate engaging in said slot, a longitudinally extending portion at said apex, and a tongue extending into said slot in opposed relation to said longitudinally extending portion for locking said projection at said apex upon relative movement of said plates to ring closing position.

2. A loose-leaf binding comprising a pair of plates relatively slidable on each other, a plurality of ring portions on each plate engageable to provide a plurality of closed rings, the ring portions of each plate being aligned in parallelism with those of the other plates, a generally V-shaped slot in one plate having its apex remote

from the ring portions of the other plates, a projection on the other plates engaging in said slot, a notch in the side of said plate portions defining said slot at said apex, and a tongue extending into said slot in opposed relation to said notch for locking said projection at said apex upon relative movement of said plate to ring-closing position.
